UNITED STATES PATENT OFFICE.

DARIUS WHITFORD, OF PROVIDENCE, RHODE ISLAND.

DESIGN FOR A WATCH-CHAIN BAR.

SPECIFICATION forming part of Design No. 19,085, dated May 7, 1889.

Application filed March 22, 1889. Serial No. 304,363. Term of patent 3½ years.

To all whom it may concern:

Be it known that I, DARIUS WHITFORD, a citizen of the United States, residing at Providence, in the county of Providence and State of Rhode Island, have invented and produced a new and original Design for Watch-Chain Bars; and I do hereby declare the following to be a full, clear, and exact description of the invention, reference being had to the accompanying drawings, and to letters or figures of reference marked thereon, which form a part of this specification.

This invention relates especially to a design for a bar for watch-chains; and it consists of a bar polygonal in cross-section, enlarged at the center and tapering therefrom to the ends, the sides of one half alternating with those of the other half.

In the appended drawings, Figure 1 represents a side view of a watch-chain bar embodying my design, and Fig. 2 is a cross-sectional view taken on line $x-x$.

The elements composing my design are as follows:

a represents the polygonal sides or facets, 25 the sides being widest at the center of the bar and tapering therefrom uniformly to the ends e . The general form or contour of the bar A is that of two pyramids united at their bases, the sides of one pyramid alternating 30 or breaking joints with those of the other, each side thereby forming and terminating in a V-shaped prolongation, a' , at the center of the bar.

What I claim is—

35 The design for a watch-chain bar having the shape and surface ornamentation herein shown and described.

In testimony whereof I have affixed my signature in presence of two witnesses.

DARIUS WHITFORD.

Witnesses:

CHARLES HANNIGAN,
GEO. H. REMINGTON.
